BUCKET FOR A BUCKET ELEVATOR

Fritz A. Callies, Menomonee Falls, Wis., assignor to Rex Chainbelt Inc., Milwaukee, Wis.

Filed Sept. 3, 1971, Ser. No. 177,911

Term of patent 14 years

Int. Cl. D15—04

U.S. Cl. D55—1 C

FIG. 1 is a top plan view of a bucket for a bucket elevator showing my new design;

FIG. 2 is a front elevation thereof;

FIG. 3 is a bottom plan view thereof;

FIG. 4 is an end elevation thereof;

FIG. 5 is a rear perspective view thereof; and

FIG. 6 is a cross-section taken on line 6—6 of FIG. 2. I claim:

The ornamental design for a bucket for a bucket elevator, as shown.
